UNITED STATES PATENT OFFICE

158,798

TYPEWRITING MACHINE

Giuseppe Prezioso, Yverdon, Switzerland, assignor to Paillard S. A., Sainte-Croix, Switzerland

Application December 10, 1948, Serial No. 150,089
In Switzerland September 8, 1948

Term of patent 14 years

(Cl. D64—11)

To all whom it may concern:

Be it known that I, Giuseppe Prezioso, a citizen of Italy, and resident of Yverdon, Switzerland, have invented a new, original, and ornamental Design for a Typewriting Machine, of which the following is a specification, reference being had to the accompanying drawing, forming part thereof.

The drawing represents as follows:

Fig. 1 is a perspective view of a typewriting machine showing my new design;

Fig. 2 is a front elevational view of the same;

Fig. 3 is a rear elevational view of the same;

Fig. 4 is a side elevational view of the same;

Fig. 5 is a top plan view thereof.

I claim:

The ornamental design for a typewriting machine, as shown.

GIUSEPPE PREZIOSO.
